UNITED STATES PATENT OFFICE.

JOHN S. THURMAN AND LYNNEAUS I. LOCKWOOD, OF ST. LOUIS, MISSOURI.

MOISTURE-EXTRACTING APPARATUS.

1,054,056.

Specification of Letters Patent. Patented Feb. 25, 1913.

Application filed March 9, 1912. Serial No. 682,802.

To all whom it may concern:

Be it known that we, JOHN S. THURMAN and LYNNEAUS I. LOCKWOOD, citizens of the United States, residing at St. Louis, State 5 of Missouri, have invented certain new and useful Improvements in Moisture-Extracting Apparatus, of which the following is a full, clear, and exact description, reference being had to the accompanying drawings, 10 forming a part hereof.

Our invention has relation to improvements in moisture-extracting apparatus, and it consists in the novel details of construction more fully set forth in the specification 15 and pointed out in the claims.

In the drawings, Figure 1 is a combined elevation and vertical section of the apparatus, parts being broken away; and Fig. 2 is an enlarged sectional detail of the control 20 valve past which the filtered air is admitted to the container or receptacle.

The object of the present invention is to construct an apparatus which is primarily intended to serve as an adjunct in laundries, 25 wherein a certain quantity of moisture must be extracted from the clothes after the same are washed preparatory to the ironing operation.

It is of course, well understood that a certain per cent. of moisture must be allowed 30 to remain in the clothes to permit the same to be ironed, the absolute drying thereof not being here intended. The present apparatus while eminently serviceable in the connection here stated, is obviously not limited 35 in its application to the treatment of clothes, but is susceptible of general application in the arts and industries where the abstraction of moisture is a desideratum.

Among the objects here sought is to provide an apparatus which possesses a maximum capacity, that is to say one which is so constructed as to permit a maximum quantity of material to be treated in a minimum 40 amount of time; one which may be successfully operated without resort to skilled labor; one which may be built at little cost and operated with little expense; one which will turn out a uniform product; one in which the articles treated are subjected to practically no deterioration; and one possessing further and other advantages better apparent from a detailed description of the invention which is as follows:—

Referring to the drawings, P represents a

rotary vacuum-pump having an intake 1 and exhaust pipe 2, the pump being operated by a belt B passing over the pulley 3 of the pump-shaft, the belt being driven from any suitable source of power (not shown). Any equivalent exhauster however will answer the purpose of the pump here conventionally illustrated. The pipe 2 may discharge into any suitable drain or sewer pipe (not shown). Secured to the intake 60 pipe or nozzle 1 is a rubber or equivalent coupling c which receives the end of the discharge nozzle 4 leading from the bottom of a collecting basin or hopper 5 identified with the bottom section 6 of a receptacle 65 or container 6', the basin 5 being provided with a perforated top or partition 7 forming the perforated bottom of the section 6' of the container. For convenience the sections 6, 6', may be jointly considered as constituting the receptacle, tank or container, 70 it being obvious that said container may be constructed in a variety of ways. The container is mounted on rollers or casters 8, and may be pulled over the floor by a handle or lever 9, the forked base of which is pivoted to the sides of the section 6. The container is closed by a lid 10, a suitable rubber gasket 11 on the receptacle making 75 a tight joint when the lid is lowered into 80 place.

From the center of the lid projects a sectional hollow standard 12 of any suitable design, in which is mounted a spring-controlled pressure or regulating valve 13 90 mounted in any way known to the art, the upper end of the standard having secured thereto a coupling 14 from which leads a tube 15. The tube serves to support the disks or heads 16, 16', between which is stretched a filter sack or screen 17, the dimensions of the disks being such as to give the sack an inverted conical contour. The disks are secured by lock-nuts n, n' in any manner well understood in the art. The upper 95 projecting terminal of the pipe is provided with a ring 18 to which is attached the end of a rope or hoisting cable h passing over sheaves or pulleys 19, 19', secured overhead and provided with a counter-weight W, the 100 opposite end of the cable being within easy reach of the operator. Between the disks 16, 16', and inside the filter screen 17, the pipe 15 is provided with a slot s or equivalent 105 openings or perforations for the pas- 110

sage therethrough of the filtered air. Within the container, the clothes of different families or customers are separated by removable perforated copper disks 20, so that they may at all times be properly identified, and separated one from the other.

The connection between the nozzle 4 and the coupling *c* is a detachable one and is necessary to carry out the general plan of operation of the apparatus, which operation may be summarized as follows:—The wet clothes *a*, *a'*, *a''*, and so forth belonging to different patrons are deposited in the receptacle 6, 6', care being taken to separate the different portions by the diaphragms 20, after which the lid 10 is lowered into position on top of the receptacle. It may be stated in passing that the receptacle has first been wheeled in front of the pump *P* and the nozzle 4 inserted into the coupling *c*. The pump or exhauster being now started, the air will naturally be exhausted (partially) from the receptacle, this action insuring a positively air-tight joint for the lid since the atmospheric air will bear down on the same in proportion to the vacuum formed in the receptacle. When the vacuum in the receptacle has reached a certain degree, atmospheric air previously thoroughly filtered by the screen 17 will flow through the slot of the tube 15 and through the hollow standard 12, past the valve 13 (the tension of whose spring 13' is overcome and the valve accordingly being unseated) into the container 6' to displace the vacuum. The action of the pump will again draw this air from the container until sufficient rarefaction results therein to again unseat the valve. Thus the pressure or regulating valve will be alternately or periodically seated and unseated, and the pump will continue operating between these two periods. During the period that the valve is closed the pump will produce a rarefaction in the receptacle or container, the air within not only becoming rarefied but at the same time expanding as it seeks an outlet through the discharge nozzle 4. During the interval that the valve is unseated, the inrush of filtered atmospheric air past the valve into the container serves to drive the moisture before it, forcing it out of the wet material into the collecting basin or funnel 5 although such expulsion is not altogether identified with the fresh currents which enter past the valve. More or less moisture is driven out by the expanding air within the container (after the valve is seated) in response to the pump action, since while the pump acts the general trend of all currents is toward the pump. The pump (or equivalent exhauster) therefore not only draws the air from the container, but the moisture as well. During the period of atmospheric expansion in the tank or container 6, 6', some moisture will

be eliminated as a result of evaporation, as it is a well known physical law that low atmospheric pressure is conducive to ready evaporation. The apparatus therefore resolves itself into two distinct modes of operation:—first, an expulsion of the moisture by atmospheric rarefaction and expansion, and second, an expulsion resulting from a mechanical dislodgment of the moisture by fresh accessions of atmospheric air into the container, the inrushing air currents driving the moisture before them. The air circulating through the container or tank should of course be perfectly clean, so that the filter or screen 17 becomes indispensable. When one lot of material has been treated, the pump is stopped, the nozzle 4 is detached from the coupling *c*, the lid 10 (now released from atmospheric pressure) is lifted, the tank wheeled out of the way and its contents removed. Another tank filled with clothes (or other material) is now wheeled in front of the pump, the connections are made as before, and the operation repeated. By this method a large quantity of material may be quickly treated. The hollow standard 12 obviously constitutes the intake for the filtered air entering the container, the nozzle 5 constituting the outlet for both air and moisture. The spring 13' may of course be set at any tension required or adjusted as well understood in the art.

Having described our invention what we claim is:—

1. A moisture extractor comprising a container, having a closed top, a hollow standard leading from the said top, an air filter carried by the standard, the walls of the standard being perforated to allow for the free travel of the filtered air into the container, a valve interposed in the path of travel of the filtered air, between the filter and container, and responding to the vacuum created in the container, a perforated bottom for the container, a collecting chamber below said bottom, and an exhauster coupled to the collecting chamber.

2. A moisture extractor comprising a container, a top removable lid therefor, a hollow standard or tube leading from the lid, an air filter carried by the standard, the walls of the standard being perforated to allow for the free travel of the filtered air into the container, a control valve mounted in the standard and responding to the vacuum created in the container, a perforated bottom for the container, a collecting chamber below said bottom provided with a discharge means, and an exhauster coupled to said discharge means.

3. In a moisture extractor, a suitable container provided with an intake, an exhauster for the container, and means responsive to the rarefaction produced by the exhauster for effecting periodic influxes of atmos-

pheric air into the container whereby the moisture therein is mechanically dislodged and driven off.

4. In a moisture extractor, a suitable container provided with an air intake, an ex-
5 hauster for the container, and means re-
sponsive to the rarefaction produced by
the exhauster for effecting periodic influxes
of atmospheric air into the container, and
10 subsequent rarefactions and expansions
within the container for the purpose set
forth.

5. In a moisture extractor, a suitable con-
tainer provided with an air intake, an ex-
15 hauster for the container, an outer air filter

operating in conjunction with the intake,
and means in the path of the filtered air and
responsive to the rarefaction produced by
the exhauster for effecting periodic influxes
of said air into the container and subsequent 20
rarefactions and expansions within the con-
tainer, for the purpose set forth.

In testimony whereof we affix our signa-
tures, in presence of two witnesses.

JOHN S. THURMAN.
LYNNEAUS I. LOCKWOOD.
